UNITED STATES PATENT OFFICE.

CYRUS B. CROSBY, OF CORTLANDVILLE, NEW YORK.

CLOTHES-RACK.

Specification forming part of Letters Patent No. **51,149**, dated November 28, 1865.

To all whom it may concern:

Be it known that I, CYRUS B. CROSBY, of Cortlandville, in the county of Cortland, in the State of New York, have invented a new and Improved Rack for Hanging Clothes to Dry; and I do hereby declare that the following is a full and exact description thereof, reference being had to the accompanying drawings, and to the letters of reference marked thereon, like letters representing like parts.

A represents a substantial staff; b, sockets, fastened to the said staff with screws and containing balls, with projections c fastened to the arms d with screws; f, vertical bars, pivoted to the arms d, which serve as a partial support, the arms being principally supported by means of the projections c from the balls of the sockets b; G, frames or wings; i, slots in the sockets, so cut that any three of the said frames or wings G may be swung together in a horizontal position, while the fourth, directly opposite,

may remain in said position or may be folded from said position by raising the arms d or sections, as represented by G, as may suit one's convenience, or may be swung around in such a position as to make, with the third wing from it a right angle, so that the said rack may be set in a corner of a room while in use, and consequently occupy but a very small space; and when not in use each frame or wing may be folded separately and adjusted vertically, as shown at K.

What I claim is—

The arrangement of the staff a, the sockets and balls b, with projections c, the arms d, and bars f, operating substantially as and for the purpose specified.

CYRUS B. CROSBY.
